ELECTRIC TIMING DEVICE

Edward B. Farmer, Waban, Mass.

Application March 3, 1951, Serial No. 213,705

8 Claims. (Cl. 250—27)

1

This invention deals with electric timing devices of the type wherein the time constant of a reactive network determines the time interval between the closing of a starting switch and the change of conductivity of a vacuum tube whose control electrode is connected to the timing network.

Previously proposed devices of this type have various defects such as sensitivity to polarity in case of sometimes unavoidable leakage through a starting switch, impossibility of connecting a load to a starting terminal, unpredictable firing of the control tube immediately upon operation of the starting component; and a tendency of tubes of some types to misfire in spite of grounding of the negative supply terminal, due to a residual charge on the timing capacitor.

Objects of the present invention are to provide a timing device which avoids the above indicated defects, which does not require standby current for its control tube, which does not require recharging time of the timing capacitor between consecutive cycles of operation, which is especially suited for comparatively short adjustable timing intervals of the approximate order of between 0.03 to 12 seconds, which is particularly suitable for operation with energy saving cold cathode gas tubes, and which is simple, small and inexpensive and yet very accurate, rugged and particularly also versatile as to adaptability to a large variety of uses including operation of spot welders, sequence control, processing, monitoring of machine output and short interval timing applications generally.

In one of its aspects, the timing device according to the invention comprises direct current supply terminals, a normally open starting switch such as the normally open contacts of a starting relay, a vacuum tube for example of the cold cathode type with anode, cathode and control electrode, a resistor of comparatively high resistance permanently connected between the anode and the cathode of the tube, connections for inserting the starting switch in series between the cathode and one of the supply terminals, a control relay which has contacts actuated by a coil, a control capacitor connected between the control electrode and the cathode of the tube, and provisions for charging the control capacitor from the supply terminals.

Other features which can be incorporated according to the invention are a normally closed starting relay contact connected across the control capacitor; connection of the power relay coil between a terminal and the anode of the tube; incorporation of a rectifying network for alternating current operation, in a manner particularly suited for the relay circuit; and a safety resistor connecting the normally closed relay contacts across the control capacitor.

2

Other objects, aspects and features will appear, in addition to those contained in the above statement of the nature and substance including some of the objects of the invention, from the following description of a typical practical embodiment illustrating its novel characteristics. This description refers to a drawing in which

Fig. 1 is the circuit diagram of an embodiment of the invention; and

Figs. 2, 3 and 4 are simplified diagrams illustrating various possibilities of using the timer according to the invention.

In Fig. 1, alternating current supply terminals are indicated at t_a and t_c . The supply line is connected to a rectifying network N with input terminals t_1 , t_2 , output terminals t_{01} , t_{02} , rectifier U , protective resistor R_1 and filter capacitor C_1 . Connected between the supply terminals is the coil L_1 of a starting relay S_1 with normally open starting contacts s_2 and normally closed safety contacts s_1 . Contacts s_1 , s_2 are preferably of the make-before-break type. In series with relay coil L is a starting contactor S_s , for example a push button switch. Terminal t is between starter relay coil and starter switch.

The anode a of a cold cathode tube G is connected to terminal t_{01} , through the coil L_2 of a power relay S_2 with normally closed contacts s_3 and normally open contacts s_4 . The cathode k is connected to terminal t_{02} through normally open contacts s_2 . Between anode a and cathode k are connected an adjustable potentiometer R_2 and the control capacitor C_c . This capacitor is normally short circuited through contacts s_1 and discharge resistor R_3 . The control electrode e is connected to point n between resistor R_2 and capacitor C_c , through a limiting resistor R_4 . A tube shunting resistor R_5 of comparatively high value is connected across anode a and cathode k .

The power relay S_2 , representing a load impedance, may have any desirable number and type of contacts; a normally closed contact s_3 and a normally open contact s_4 are shown by way of example. A load Z , controlled by the power relay or other tube controlled impedance able to develop a suitable potential is indicated as connected to the supply terminals through contacts s_4 .

In an embodiment for average purposes, the ratings of the principal elements are as follows:

Resistors:

R_1 , R_3 , 50 ohm
 R_2 , 10,000 ohm fixed and 10 megohm potentiometer

R_4 , R_5 , 56,000 ohm

Capacitors:

C_1 , 40 mfd. electrolytic
 C_c , .25 mfd.—2.0 mfd.

Tube: Cold cathode, type 5823 gas tube

The above described device operates as follows:

When starting switch S_s is closed, coil L_1 is energized which in turn closes contacts s_2 and applies the direct potential between terminals t_{01} , t_{02} to anode and cathode of the tube G . Electrode e is at that time at cathode potential, having been connected to the cathode through contacts s_1 . With contacts s_1 opened and s_2 closed by coil L_1 , the control capacitor C_c begins to charge at a rate determined by potentiometer R_2 . When the voltage at n reaches the firing potential of tube G , the circuit containing coil L_2 of power relay S_2 is closed and contacts s_3 , s_4 transferred, completing the timing interval. It is assumed that starting switch S_s is retained closed during the timing cycle, or that an appropriate holding device is provided. It will be understood that electrode e loses control of tube G after it has fired, and that the tube and relay S_2 are deenergized after S_s is opened, so that the circuit is then reset and ready for the next cycle.

The normally closed contact s_1 of starting relay S_1 holds the starting electrode e essentially at cathode potential during all standby time. This also prevents the control or timing capacitor C_c from picking up charge due to leakage. When starting relay S_1 is energized by starter switch S_s , the short circuit across timing capacitor C_c is removed and the timing network is instantly connected to line. Since S_1 operates in about one half cycle and its speed of operation can be made quite constant, it introduces very little error into the timing cycle.

During the standby period, the timing network is isolated from terminal t_c by normally open contact s_2 , so that any load connected to t_c will not affect the timing. The presence of a load on t_c after closure of s_2 does not have any effect.

A resistor R_5 large enough to prevent power relay S_2 from operating when in series therewith was found to eliminate all tendency of tube G to misfire with either line polarity; this feature constitutes an important improvement with regard to certainty of operation.

The discharge resistor R_3 goes into effect upon closing of contact s_2 .

While not absolutely necessary for good operation, the use of make-before-break contacts on relay S_1 prevents a small charge from entering the timing capacitor C_c while the relay contacts transfer, which charge might slightly affect the timing interval.

It will be understood that the device can be operated directly from a direct current supply, when rectifier N can be omitted.

Figs. 2, 3 and 4 indicate various ways in which the device according to Fig. 1 can be connected. In each of these figures, a block T indicates a timer according to Fig. 1, with the terminals and switches identified as in Fig. 1.

With connections according to Fig. 2, the load Z_1 is deenergized after the time delay, and the load Z_2 is energized after the delay.

With connections according to Fig. 3, the load Z is energized at the start, and deenergized at the end of the timing period.

The connection according to Fig. 4 provides a repeat cycle; timer T_1 controls the "on" time whereas timer T_2 controls the "off" time.

It should be understood that the present disclosure is for the purpose of illustration only and that this invention includes all modifications

and equivalents which fall within the scope of the appended claims.

I claim:

1. A timing device comprising direct current supply terminals; normally open starting contacts; a tube of the gaseous cold cathode type with anode, cathode, and control electrode; a resistor of comparatively high value permanently and free of said control electrode connected between said anode and said cathode; means connecting said starting contacts between said cathode and one of said terminals; a control relay having a coil for closing said starting contacts; a control capacitor connected between the control electrode and cathode of said tube; and means for charging said capacitor from said terminals upon closure of said starting contacts.

2. A timing device comprising direct current supply terminals; a control relay having normally open starting contacts and normally closed contacts and a coil for actuating said contacts; a tube of the gaseous cold cathode type with anode, cathode and control electrode; means connecting said normally open starting contacts between said cathode and one of said terminals; a load impedance in circuit with said anode and cathode; a control capacitor connected between the control electrode and cathode of said tube; means for charging said capacitor from said terminals upon closure of said starting contacts; and means connecting said normally closed contacts of the control relay across said capacitor.

3. A timing device comprising direct current supply terminals; a control relay having normally open starting contacts and normally closed contacts in make-before-break arrangement and a coil for actuating said contacts; a tube of the gaseous cold cathode type with anode, cathode and control electrode; means connecting said normally open starting contacts between said cathode and one of said terminals; a load impedance connected in circuit with said anode and cathode; a control capacitor connected between the control electrode and cathode of said tube; means for charging said capacitor from said terminals upon closure of said starting contacts; and means connecting said normally closed contacts of the control relay across said capacitor.

4. A timing device comprising direct current supply terminals; a control relay having normally open starting contacts and normally closed contacts and a coil for actuating said contacts; a tube of the gaseous cold cathode type with anode, cathode and control electrode; a resistor of comparatively high rating permanently and free of said electrode connected between said anode and said cathode; means connecting said normally open starting contacts between said cathode and one of said terminals; a load impedance in circuit with said anode and cathode, in series with said resistor with the tube nonconductive; a control capacitor connected between control electrode and cathode of said tube; means for charging said capacitor from said terminals upon closure of said starting contacts; and means connecting said normally closed contacts of the control relay across said capacitor.

5. A timing device comprising supply terminals for connection to an alternating current source; a rectifying network having two input and two output terminals; connections between said supply and said input terminals; a normally open starting switch; a control relay having a set of normally open starting contacts, a set of normally closed safety contacts and a coil con-

nected through said starting switch between said input terminals for actuating said contacts upon closure of said starting switch; a tube of the gaseous cold cathode type with anode, cathode and control electrode; a load impedance in circuit with said anode and cathode; means connecting said normally open starting contacts of said control relay between said cathode and the second output terminal; a control network including a capacitor and resistance means connected in series between said first output terminal and said cathode, with the capacitor on the cathode and the resistor on the output terminal; a resistor leading from the connection between said capacitor and said resistance means to said control electrode; and means connecting said normally closed safety contacts of said control relay across said capacitor.

6. A timing device comprising supply terminals for connection to an alternating current source; a rectifying network having two input and two output terminals; connections between said supply and said input terminals; a normally open starting switch; a control relay having a set of normally open starting contacts, a set of normally closed safety contacts and a coil connected through said starting switch between said input terminals for actuating said contacts upon closure of said starting switch; a tube of the gaseous cold cathode type with anode, cathode and control electrode; a resistor of comparatively high rating permanently and free of said electrode connected between said anode and said cathode; a load impedance in circuit with said anode and cathode, in series with said resistor with the tube nonconductive; means connecting said normally open starting contacts of said control relay between said cathode and the second output terminal; a control network including a capacitor and resistance means connected in series between said first output terminal and said cathode, with the capacitor on the cathode and the resistor on the output terminal; a resistor leading from the connection between said capacitor and said resistance means to said control electrode; and means connecting said normally closed contacts of said control relay across said capacitor.

7. A timing device comprising supply terminals for connection to an alternating current source; a rectifying network having two input and two output terminals; connections between said supply and said input terminals; a normally open starting switch; a control relay having a set of normally open starting contacts and a set of

normally closed safety contacts in make-before-break arrangements of said contacts, respectively, and a coil connected through said starting switch between said input terminals, for actuating said contacts upon closure of said starting switch; a tube of the gaseous cold cathode type with anode, cathode and control electrode; a resistor of comparatively high rating permanently and free of said electrode connected between said anode and said cathode; a load impedance in circuit with said anode and cathode, in series with said resistor with the tube nonconductive; means connecting said normally open starting contacts of said control relay between said cathode and the second output terminal; a control network including a capacitor and resistance means connected in series between said first output terminal and said cathode, with the capacitor on the cathode and the resistor on the output terminal; a resistor leading from the connection between said capacitor and said resistance means to said control electrode; and means including a resistor of low resistance connecting said normally closed contacts of said control relay across said capacitor.

8. A timing device comprising direct current supply terminals; a tube of the gaseous cold cathode type with anode, cathode and control electrode; terminals providing for connection of a controlled high impedance means in series with said anode and cathode; a resistor connected permanently and free of said control electrode across said cathode and anode, said resistor having a value sufficiently high to prevent appreciable voltage drop across said impedance means when said tube is non-conductive with impedance means and resistor in series; and means adapted to connect said anode and said cathode to respective terminals and to bring said control electrode to firing potential.
